UNITED STATES PATENT OFFICE.

EVAN LEWIS, OF SWANSEA, WALES.

REVERSING-VALVE OF GAS-FIRED SMELTING-FURNACES AND THE LIKE.

1,146,582.

Specification of Letters Patent.

Patented July 13, 1915.

Application filed November 2, 1914. Serial No. 369,855.

To all whom it may concern:

Be it known that I, EVAN LEWIS, a subject of His Majesty the King of England, residing at Swansea, in the county of Glamorgan,

5 South Wales, have invented certain new and useful Improvements in and Relating to the Reversing-Valves of Gas-Fired Smelting-Furnaces and the like, of which the following is a specification.

10 This invention relates to reversing valves of gas fired smelting furnaces and the like having yielding valve seats of refractory material.

I will now describe my invention with 15 reference to the accompanying drawings in which:—

Figure 1 is a diagrammatical sectional elevation; Fig. 2 is an end elevation, parts being broken out to show the opening in the 20 wall for the sliding tray. Fig. 3 is a sectional plan of a furnace top fitted with my improved valves.

As shown the main reversing flap valve *a* is rotatably mounted below the gas inlet 25 and gas box in a casing or bonnet *b* of usual construction, which is disposed above the furnace *c* and provided with side chambers *d* to allow the gas to enter the furnace *c* at one end *e* and to be drawn off to connect 30 with the flue *f* in communication with the stack shaft at the other end or vice-versa. This reversing valve *a* is disposed in the middle of the divided casing *g* and is mounted on a shaft *h* at its lower end in the said 35 casing in such a manner that when operated by a lever *i* fitted externally of the casing and preferably connected through links to a hand lever provided on a gantry or platform *j* disposed above the furnace, the valve 40 *a* is adapted to close either of the chambers *d* and to put the other into communication with the gas supply. This reversing valve *a* constructed according to my invention, is provided with curved over lips or longitudinal 45 projections *a'* on opposite sides respectively of its outer end, and one lip is adapted to lie, when the valve *a* is in its closed position in a tray *a'* and the other in a tray *a''* containing sand or the like. This tray 50 *a'* or *a''* is slidably mounted on a shelf *7* above one of the openings *d'* communicating with one of the side chambers *d* so that either tray *a'* or *a''* can be withdrawn from the casing *b* through slots 11 in the front wall 55 10 thereof and the sand contained in said

trays can be changed or replenished when required. Each tray *a'* is provided at one end with a plate 5 having a handle 6 as shown in Figs. 2 and 3.

The side wall *a³* of either tray *a', a''* against which the valve is adapted to lie is preferably sloped or shaped so as to provide a gas tight joint. It will thus be seen that should the outer end of the valve *a* curve, or warp, as it usually does owing to the excessive heat, 65 a gas tight joint can still be obtained by reason of its end *a'* dipping into a bank of sand or other refractory material.

Each side chamber *d* is provided with an inlet or an outlet *k* to or from the furnace 70 and an outlet *f* to the stack shaft but when the previously described reversing valve *a* is in a position to allow the gas to communicate through one of the chambers *d* to one side *e* of the furnace *c*, the outlet *f* from this chamber to the stack must be closed and the outlet *f* to the stack in the other side chamber *d* opened. The valves *l* for opening or closing these outlets *f* are usually of "pot lid" shape and are hung on the opposite 75 ends of a lever which is connected to the reversing valve. According to my invention I make these valves *l* of tapered form so as to enter and close the opening *f* to the flue. These valves *l* are weighted and hung on rods *m* which pass through holes *n* in the casing *d* and are connected to each other by a chain *o* or the like which is adapted to pass over pulleys or wheels *p* mounted above the casing so that when one valve *l* is open the other is closed. This chain *o* is connected by a suitable link *q* to an endless chain *r* passing over pulleys *s* hung from the before mentioned platform *j* and is operated by a handwheel, not shown, on the platform 80 through any suitable gear such as another endless chain passing over pulleys one of which is connected to one of the first mentioned pulleys *s*.

What I claim as my invention and desire to secure by Letters Patent of the United States is:—

The combination with a gas fired furnace of a valve casing having openings in its top and side walls and shelves above said side wall openings and slots in its front wall, said casing being provided at opposite points on its side walls with valve seats composed of sliding trays containing sand and adapted to be withdrawn through said slots, an 105 110

oscillatory valve pivoted between said side walls and provided with flanges at its opposite outer edges adapted to engage in inclined position either of said valve seats, and 5 flues connecting said casing with said top and said openings.

In testimony whereof I have signed this

specification in the presence of two subscribing witnesses.

EVAN LEWIS.
